UNITED STATES PATENT OFFICE.

EMIL BERDUX, OF MUNICH, GERMANY, ASSIGNOR TO THE FIRM OF V. BERDUX, OF MUNICH, GERMANY.

PIANOFORTE.

983,529.

Specification of Letters Patent.

Patented Feb. 7, 1911.

Application filed September 30, 1909. Serial No. 520,280.

To all whom it may concern:

Be it known that I, EMIL BERDUX, a subject of the German Emperor, residing at Munich, Germany, have invented certain new and useful Improvements in Pianofortes, of which the following is a specification.

My invention relates to improvements in pianofortes, and has especial reference to 10 means for so improving the structure and combination of the brace bars on the string plate and sounding-board bridge that the resistance of the frame will be increased, thus obviating its tendency to bend under 15 stress.

The principal object of my invention is to provide a construction of pianoforte in which the tone will be of the highest quality and the structure such that bending of the 20 frame is practically impossible under the severe strains put upon it by the strings.

In carrying my invention into practice I groove or cut away a portion of certain of the brace bars so that the bridge of the 25 sounding board may pass through the groove in the brace bar, and I insert through a bore in the bridge, without touching the latter, a member which may either be secured to the brace-bar or form an integral part thereof. The brace bars are 30 preferably provided with strengthening ribs to compensate for any loss of rigidity which may be occasioned by grooving the same, and the member passes through the 35 neutral axis of the bridge so that the latter is not weakened. I thus, in fact, strengthen the frame and increase its resistance under the strain of the tensioned strings, thereby 40 improving the tone of the instrument.

The invention is illustratively exemplified in the accompanying drawing, wherein—

Figure 1 is a plan view of a portion of a pianoforte provided with my invention; Fig. 2 is a cross sectional view on the line 45 A—B of Fig. 1; and Fig. 3 is a cross sectional view of a modified form of the invention.

Referring by reference characters to the drawing, and particularly to Figs. 1 and 2 thereof, *a* designates suitably formed brace bars on the string plate some of which are 50 preferably provided with strengthening ribs *h*. Certain of the brace bars are grooved or cut away at *b* to permit the bridge *c* of the sounding board *s* to pass

through such grooves. The bridge *c* is provided with transverse bores *d* through each of which is passed a pin *f*, each end thereof being held by a screw *g* to the brace bar *a* in an undercut portion of the groove *b*. 60 The pins *f* serve the function of strengthening members for the brace bars *a*, and tend to prevent the latter from bending under strain. Only certain of the brace bars are shown as engaging the bridge; those in 65 proximity to the bass portion of the string plate may not be extended into proximity to the bridge, and may be strengthened in any suitable manner. The string plate is provided with longitudinal strengthening bars 70 *i* and *k*, the bar *i* being apertured at *l* to permit the bass strings to pass therethrough, and being secured to the plate by screws *m*.

In Fig. 3 I have shown a modified method 75 of passing the bridge *c* through the brace bars *a*. The brace bar *a* in this form is provided with an aperture *d'* the lower edge of the metal web *a'* being left intact. The bridge *c* is provided with an angular bore 80 *b'* through which the edge *a'* passes without touching the bridge. The purpose and effect of the interconnection of brace bar and bridge are the same in Figs. 2 and 3, the bores *d* and *b'* in each case being just 85 large enough to prevent the bridge from contacting with the pin *f* or edge *a'*.

It will be noted from Figs. 2 and 3, that the brace bars have been deepened or increased in width over the ordinary brace 90 bars, in the direction of the sounding board and in this way the plane of the strings is brought to a line corresponding nearly with the center line of the brace bars, so that when the strings are tensioned the strains 95 will be more evenly distributed on the increased cross section of the brace bars.

Having thus described my invention, what I claim as new and desire to secure by Letters Patent is:

1. In pianofortes, the combination with the string plate and the brace bars thereon having grooves formed therein, of the sounding-board bridge having transverse bores and passing through the grooves in the brace bars, and strengthening members for the brace bars connected to the latter and passing through the bores in the bridge. 105

2. In pianofortes, the combination with the string plate and the brace bars thereon 110

having grooves formed therein, of strengthening ribs carried by said brace bars in proximity to the grooves, the sounding board bridge having transverse bores and passing through said grooves, and strengthening members for the brace bars connected to the latter and passing through the bores in the bridge.

3. In pianofortes, the combination with the sounding-board and bridge, the latter being provided with transverse bores, of the brace bars on the string plate, said brace

bars having their lower edges in proximity to the sounding-board and being provided with grooves through which the bridge 15 passes, and strengthening members for the brace bars connected to the latter and passing through the bores in the bridge.

In testimony whereof I have affixed my signature in presence of two witnesses.

EMIL BERDUX.
